UNITED STATES PATENT OFFICE.

GEORGE A. ENSIGN, OF DEFIANCE, OHIO, ASSIGNOR TO THE DEFIANCE MACHINE WORKS, OF DEFIANCE, OHIO, A CORPORATION OF OHIO.

WOOD-TURNING LATHE.

SPECIFICATION forming part of Letters Patent No. 690,253, dated December 31, 1901.

Application filed May 9, 1901. Serial No. 59,402. (No model.)

To all whom it may concern:

Be it known that I, GEORGE A. ENSIGN, a citizen of the United States, and a resident of Defiance, in the county of Defiance and State 5 of Ohio, have invented a new and Improved Wood-Turning Lathe, of which the following is a full, clear, and exact description.

The object of the invention is to provide a new and improved wood-turning lathe more 10 especially designed for producing in large quantities duplicate articles—such as bobbins, handles, spoons, mallets, stakes, pins, and the like, either plain or with beads—the lathe being arranged to reduce the rough material 15 to the finished product complete in every respect and the exact shape and size, perfectly smooth and exceedingly accurate.

The invention consists of novel features and parts and combinations of the same, as 20 will be fully described hereinafter and then pointed out in the claims.

A practical embodiment of the invention is represented in the accompanying drawings, forming a part of this specification, in which 25 similar characters of reference indicate corresponding parts in all the views.

Figure 1 is a perspective view of the improvement. Fig. 2 is a plan view of the same with parts in section, and Fig. 3 is an 30 enlarged sectional side elevation of the device for discharging the work from the centers of the head-stock and the tail-stock.

The wood-turning lathe is mounted on a suitably-constructed frame A, in which is 35 journaled a cutter-head spindle B, carrying a sufficient number of individual cutter-heads C for covering the entire length of the work D, turned its full length at one operation, as hereinafter more fully described. On one 40 end of the spindle B is secured a pulley E, connected by a belt E' with other machinery for imparting a rotary motion to the spindle B and the cutter-heads C.

The work D is held on the usual head-stock 45 center F and a tail-stock center G, of which the center F is secured on a driven spindle H, journaled in the usual head-stock bearings H', carried by a table I, and the center G is mounted to slide longitudinally in a tail- 50 stock J, held adjustably in a transverse as well as a longitudinal direction on the table

I. The latter is mounted to travel transversely to bring the work D into proper position for the cutter-heads C to turn a rough stick to the desired shape. The table I is 55 for this purpose provided on its under side with grooved wheels I', mounted to travel on transversely-extending rails I², secured to or forming part of the frame A. On the under side of the table I is secured a bracket I³, 60 pivotally connected by a link K with the upper end of an arm K', secured on a shaft K², journaled in suitable bearings on the frame A, and on said shaft K² is secured a handle K³, adapted to be taken hold of by the 65 operator to impart a rocking motion to the shaft K² and cause the arms K' to move the link K, and consequently the table I, transversely to bring the work to the cutter-heads C or to move it away from the same, accord- 70 ing to the direction in which the handle K³ is moved. The inward sliding movement of the table I is limited by a screw-rod I⁴ under the control of the operator and screwing in a nut I⁵, carried by the table, the inner end of 75 said screw-rod being adapted to abut against the front of the frame A at the time the table I moves to its innermost position. By adjusting the screw-rod I⁴ the axis of the head- 80 stock is brought nearer to or farther from the axis of the cutter-head spindle B at the time the table I is in an innermost or working position.

On the outer end of the head-stock spindle H is secured a gear-wheel H², in mesh with a 85 pinion H³, secured on a shaft H⁴, journaled in an arm H⁵, mounted to swing loosely from the spindle H as a fulcrum, and on said shaft H⁴ is secured a pulley H⁶, connected by a belt H⁷ with other machinery for imparting 90 a rotary motion to the shaft H⁴, the pinion H³, and gear-wheel H² to rotate the head-stock spindle H comparatively slow relatively to the rotary motion given to the cutter-head spindle B. By having the arm H⁵ and the 95 parts carried thereby mounted to swing it is evident that the arm adjusts itself on moving the table I transversely, so that the belt H⁷ always has the proper tension.

In order to readily discharge the finished 100 article from the centers F and G, the following device is provided: On the outer end of

the tail-stock center G is formed or secured a bearing L, engaged by a block L', held on the eccentric-pin L² of an eccentric L³, mounted to turn in a suitable bearing L⁴, attached 5 to the tail-stock J, as indicated in Fig. 2. On the eccentric L³ is secured a handle L⁵, adapted to be taken hold of by the operator to turn the eccentric L³ in its bearing L⁴, so that the pin L² imparts longitudinal movement to the 10 block L', and consequently to the bearing L and the tail-stock center G, to move the latter in or out of engagement with the work D. Thus when the handle L⁵ is in the position shown in Figs. 1 and 2 the tail-stock center 15 G is in engagement with the end of the work D, and when the operator throws the handle L⁵ over from the left to the right then the tail-stock center G is moved in a like direction and out of engagement with the end of 20 the work D. It is understood that the block L' is free to slide vertically in the bearing L; but by turning the eccentric L³ a longitudinal shifting movement is given to the tail-stock center for the purpose mentioned. 25 The work D is pushed off the head-stock center F after the tail - stock center G is moved out of engagement with its end of the work D, and for this purpose a pusher N in the form of a sleeve is mounted to slide on 30 the head-stock center F to engage the end of the work D and push the latter off said center F on shifting the pusher N from the left to the right. The movement of the pusher in the direction mentioned is controlled from 35 the tail-stock center G, and for this purpose the said pusher N is engaged by a shifting-lever N', fulcrumed at N² on the table I, the lever being pressed on by a spring N³ to hold the pusher N normally out of engagement 40 with the work D in the position shown in the drawings. The shifting-lever N' is pivotally connected with one end of a rod N⁴, having its other end mounted to slide in bearings N⁵, attached to the table I. On the rod N⁴ is held 45 longitudinally, adjustably, an arm O by means of a set-screw O', and in said arm O screws a set-screw O², adapted to be engaged by the outer end of a bearing L, so that when the latter is shifted from the left to the right, as previously explained, and the tail-stock center G 50 has moved out of engagement with its end of the work D, then the bearing L, on a further movement to the right, engages the set-screw O² and moves the arm O and rod N⁴ from the left to the right to swing the shifting-lever N' in a like direction against the tension of the spring N³, so that the pusher N is moved on the head-stock center F to push the work D off said center F. When this takes place, 55 the finished work drops and is discharged from the machine. The operator now places a large stick in position on the center F and then throws the handle L⁵ over, back to the forward position, (shown in Figs. 1 and 2,) so that the tail-stock center G engages the other end of the work. The work is now supported 60 and is rotated with the head-stock spindle H

and the center F, and the operator now swings the handle K³ inward, so that the table I, with the work, is moved transversely, and the work 70 is brought in contact with the cutter - heads C, so that the latter turn the work throughout its length, the work being finished as soon as the screw-rod I⁴ abuts against the frame A. When this takes place, the operator throws 75 the handle K³ back, to move the table I to the front, and then the operator swings the handle L⁵ from the left to the right to discharge the work from the centers F and G, as above explained. The usual hood P extends over 80 the cutter-heads C, as shown in the drawings.

Having thus fully described my invention, I claim as new, and desire to secure by Letters Patent—

1. A wood-turning lathe, comprising a revolvable spindle carrying a plurality of cutters, a table mounted to travel transversely toward and from the cutters, a head-stock mounted on the table, a driving - pulley mounted in a swinging support carried by the table and 90 geared with the head-stock, a tail-stock on the table, and means for operating the table, as set forth.

2. In a lathe, the combination with the head-stock, the tail-stock provided with a bearing 95 at one end, and means for engaging the bearing to impart a longitudinal movement to the tail-stock, of a sliding and spring-pressed pusher loosely mounted on the head - stock spindle, a sliding rod having one end connected with the pusher, and an arm secured to the said rod and having its free end extending in front of the bearing on the end of the tail-stock, as set forth.

3. In a lathe, the combination with a sliding table and a head-stock, having a gear-wheel on its spindle, of an arm mounted to swing on said spindle, and a shaft mounted in said arm and provided with a pulley and with a pinion meshing with the gear-wheel 110 on head-stock spindle, as set forth.

4. A wood-turning lathe having a discharging device for the finished work, comprising a guideway on the tail-stock center, a block 115 vertically slidable therein, and an eccentric mounted to turn and engaging said block, to impart a sliding motion to the tail-stock center, as set forth.

5. A wood-turning lathe having a discharging device for the finished work, comprising 120 a guideway on the tail-stock center, a block vertically slidable therein, a handled eccentric adapted to be turned by the operator and engaging said block, to move the tail-stock center longitudinally, a pusher movable longitudinally on the head-stock center, to engage the work and push it off said head-stock center, and a shifter for said pusher and adapted to be engaged by said guideway, as set forth.

6. A wood-turning machine having a discharging device for the finished work, comprising a guideway on the tail-stock center, a block vertically slidable therein, a handled

- eccentric adapted to be turned by the operator and engaging said block, to move the tail-stock center longitudinally, a pusher movable longitudinally on the head-stock center, to engage the work and push it off said head-stock center, and a shifter for said pusher and adapted to be engaged by said guideway, said shifter comprising a spring-pressed shifting-lever, a rod connected with said lever, and an arm adjustable on the rod and adapted to be engaged by said guideway, as set forth.
7. A wood-turning lathe having a discharging device for the finished work, comprising a guideway on the tail-stock center, a block vertically slidable therein, a handled eccentric adapted to be turned by the operator and engaging said block, to move the tail-stock center longitudinally, a pusher movable longitudinally on the head-stock center, and a shifter for said pusher and adapted to be engaged by said guideway, said shifter comprising a spring-pressed shifting-lever connected with said pusher, a rod pivotally connected with said lever and mounted to slide at its free end, an arm adjustable on said rod, and a set-screw on the arm and adapted to be engaged by said guideway, as set forth.
8. In a wood-turning lathe, the combination with the head-stock, the tail-stock, and means for moving the tail-stock longitudinally, of a pusher loosely mounted on the head-stock spindle, a pivoted and spring-pressed shifting-lever engaging the pusher and normally holding it out of engagement with the work, and a sliding rod connected with the shifting-lever and provided with an arm having its free end extending into the line of movement of the tail-stock to be engaged thereby when it is moved, as and for the purpose set forth.
- In testimony whereof I have signed my name to this specification in the presence of two subscribing witnesses.
